UNITED STATES PATENT OFFICE.

WILLIAM L. JACOBY, OF MAYWOOD, ILLINOIS, ASSIGNOR TO LATROBE STEEL & COUPLER COMPANY, OF PHILADELPHIA, PENNSYLVANIA, A CORPORATION OF NEW JERSEY.

CAR-COUPLING.

SPECIFICATION forming part of Letters Patent No. 748,740, dated January 5, 1904.

Application filed August 8, 1903. Serial No. 168,693. (No model.)

To all whom it may concern:

Be it known that I, WILLIAM L. JACOBY, a citizen of the United States, residing in Maywood, in the county of Cook and State of Illinois, have invented a new and useful Improvement in Car-Couplers, of which the following is a specification.

My invention relates to car-couplers of the M. C. B. or Master Car-Builders' type, having a forked draw-head and pivoted knuckle and gravity lock, and more particularly of the particular style of Master Car-Builders' couplers which is commonly known in trade as the "Chicago" coupler and wherein the lock consists of a longitudinal bar lying in the chamber of the draw-bar and pivoted there-to at its inner end and engaged near its outer end by a vertically - moving coupling - pin. Couplers of this general type are illustrated in the patents to William S. Schroeder and Deyo, No. 412,879, and Schroeder and Lindholm, No. 509,104. Heretofore in this so-called "Chicago" coupler it has been customary to employ a separate pivot - pin at the extreme inner end of the longitudinal locking-bar to connect it to the draw-bar and keep it in position and prevent it from being removed and becoming lost, the pivot-pin itself requiring a key or other fastener.

The object of my invention is to provide an improved construction whereby the pivotal longitudinal locking - bar may be pivotally connected to the draw - bar and at the same time kept in position and prevented from accidental displacement when in operation without requiring the use of a separate pivot-pin and its key, thus lessening the number of parts and simplifying the construction of the coupler.

My invention consists in the means I employ to practically accomplish this object or result—that is to say, it consists in providing a longitudinal pivotal locking-bar with an integral pivot-lug and a curved nose and rear end and the interior chamber of the draw-bar with coöoperating pivot - saddles and a curved guide-rib coöoperating with the curved nose and curved rear end of the locking-bar to pivotally connect the locking-bar with the draw-bar to permit the rear or pivot end of

the locking-bar to be inserted in and removed from the saddle by two movements, one longitudinal and the other downward, when the free or outer end of the locking-bar is lifted, while at the same time preventing the removal or displacement of the rear or pivot end of the locking-bar from the saddle of the draw-bar, except by the double movement above mentioned and when the outer end of the locking-bar is in its uppermost position. The coupling-pin and other parts of the coupler coöperate to prevent the lock from having the two movements necessary for the removal of its pivot end from the saddle of the draw-bar, except when the coupling-pin itself is first removed. While my invention thus obviates the necessity for employing a separate pivot-pin and pivot-pin key, the pivot-pin and its key may be also employed, if desired; but with my invention there will be no danger of the lock becoming displaced, even if the key and separate pivot-pin should become loose or removed.

My invention also consists in the novel construction of parts and devices and in the novel combinations of parts and devices herein shown or described.

In the accompanying drawings, forming a part of this specification, Figures 1 and 2 are vertical longitudinal sections of a car-coupler embodying my invention, showing the parts in different positions. Fig. 3 is a horizontal section. Fig. 4 is a cross-section on line 4-4 of Fig. 3. Fig. 5 is a detail perspective view of the coupling-pin, and Fig. 6 is a detail vertical sectional view of the longitudinal locking-bar.

In the drawings, A represents the draw-bar; A', the forked draw-head, having the customary pivot-arm A² and guard-arm 3.

B is the knuckle pivoted to the draw-head by the pivot-pin C and having the tail B', which is engaged by the longitudinal pivotal locking-bar D, which fits and lies in the chamber a of the draw-bar.

F is the coupling-pin by which the free or outer end of the longitudinally-extending pivotal locking-bar D is operated or lifted to unlock the coupler or permit the knuckle to swing open. The longitudinal locking-bar D

is provided at its rear or pivotal end with pivot-lugs d and also with a curved nose d' and a curved rear end or guide d^2 . The draw-bar A is provided inside the chamber a , on its lower web or floor with saddles or ribs a' , having pivot notches or recesses a^2 therein to receive the pivot-lugs d at the rear end of the locking-bar, and it is also provided with a curved guide-rib a^3 , projecting downwardly from its upper web and which fits above the curved guide or rear end of the locking-bar D when the same is in position in the saddle. The curved guide a^3 , the saddle, and the curved guide or rear end d^2 and nose d' of the locking-bar are preferably shaped about as illustrated in the drawings and coöperate together to prevent the locking-bar being displaced or removed from the saddle, except when its front end is disconnected from the coupling-pin and except by then first lifting the free end of the locking-bar upward and then giving its rear end first an upward and then a longitudinal movement, thus withdrawing its pivot-lugs from the saddle-notches, which are also shaped to coöperate with the curved guides a^3 on the draw-head and d^2 at the rear end of the locking-bar. The lower web or floor of the draw-head is provided with a slot or recess a^4 to receive the curved nose d' of the locking-bar.

The locking-bar D is provided at its front end with a chamber d^4 , having an opening d^5 large enough to receive the head or shoulder f on the coupling-pin F, and provided with a slot d^6 to receive the web f' , which connects the head or shoulder f with the coupling-pin F. The locking-bar is provided with a projection d^7 , which engages a projection a^5 on the draw-bar and serves as a guide.

40 I claim—

1. In a car-coupler, the combination with a pivoted knuckle and forked draw-head, of a draw-bar having a chamber to receive a longitudinal pivotal locking-bar, and provided with a pivot-saddle and a curved guide-rib above the pivot-saddle, of a longitudinal pivotal locking-bar, having integral pivot-lugs fitting in the notches of the saddle and provided with a curved rear end and nose coöperating with the saddle and curved guide of

the draw-bar to keep the pivotal locking-bar in position and prevent its removal, except by two movements, one upward and the other outward, when the free end of the locking-bar is lifted and disconnected from its coupling-pin, and a coupling-pin removably attached to the free or outer end of the locking-bar, substantially as specified. 55

2. In a car-coupler, the combination with a pivoted knuckle and a forked draw-head, of a draw-bar, a pivotal locking-bar lying lengthwise in the chamber of the draw-bar and a coupling-pin detachably connected with the free end of the locking-bar, said draw-bar having an integral pivot-saddle for the rear end of the locking-bar and an integral guide above the pivot-saddle, and said locking-bar having integral pivot-lugs and a curved rear end coöperating with said guide, on the draw-bar to prevent removal except by two movements, substantially as specified. 60

3. The combination with a pivoted knuckle, and a forked draw-head and draw-bar, of a locking-bar pivoted in the chamber of the draw-bar at its rear end, a coupling-pin detachably connected with the free or outer end of the locking-bar, said draw-bar having an integral pivot-saddle furnished with pivot-notches, and provided with an integral guide-rib above the pivot-saddle, and said locking-bar having a pivot-lug at its rear end and a curved guide and nose, substantially as specified. 75

4. The combination with a pivoted knuckle, a forked draw-head and draw-bar, of a pivotal locking-bar extending lengthwise in the chamber of the draw-bar and provided with a chamber d^4 having an opening d^5 , a slot d^6 and a coupling-pin F having a head or shoulder f and web f' to detachably connect the same with said locking-bar, said locking-bar having also pivot-lugs d and a curved rear end or guide d^2 , and said draw-bar having an integral pivot-saddle a' and a curved guide-rib a^3 above said pivot-saddle, substantially as specified. 80 85
